UNITED STATES PATENT OFFICE.

FRANK D. GORMAN, OF NEW YORK, N. Y.

IRONING BOARD.

Application filed August 26, 1926. Serial No. 131,704.

The present invention is concerned with the provision of improvements in ironing boards, particularly with the provision of a board designed for facilitating the proper ironing of collars and cuffs.

The type of turn-over cuffs which are now commonly used on men's shirts are difficult to correctly iron, because when the cuffs are folded over and ironed, the button-holes are frequently out of alignment, with the result that when the cuff buttons are subsequently applied, there will be a tendency for the cuffs to fold on lines other than the crease made by the iron, and the cuffs present an untidy appearance. The same thing is true of soft collars and for generally similar types of garment, in which it is desirable to fold two plies of material, one upon the other and iron them with the button-holes of each ply in proper alignment.

In accordance with the present invention, I eliminate these difficulties, and provide an ironing board which will insure the correct ironing of this class of garments.

The board will also greatly expedite the ironing operation, is of simple, practical construction, rugged, durable and efficient in use, capable of manufacture with comparative economy, and carrying readily adjustable means for receiving and holding different sized collars, cuffs and other articles.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a top plan view of an ironing board embodying the present invention, the dotted lines indicating the cuff portion of a soft shirt in position, with the cuff folded over and both sets of button-holes received by the pins or studs.

Fig. 2 is a view in longitudinal section on the line 2—2 of Fig. 1.

Fig. 3 is an enlarged perspective view of one of the adjustable retaining studs.

Fig. 4 is a perspective view similar to Fig. 3, illustrating a modification.

In the drawings I have used the reference character 10 to designate an ironing board of any convenient size and shape which may be supported at its corners upon legs 11. A

relatively thin elongated metal plate 12 is inlaid in a shallow recess 13 in the upper surface of the board, being secured in position by screws or other appropriate securing devices 14. Screwed into an opening in the board 10 through one end of the plate 12 is the threaded shank 15 of a retaining stud 16, the stud being shouldered at 17 to limit the entrance of the shank through the board. Wing nuts 18 or other suitable clamping devices screwed on to the lower end of the stud and tightened against the bottom of the board 10 retain this stationary stud member in place. The stud 16 is preferably flattened as best seen in Fig. 3, and locked in position with its major axis coincident with the plane of an elongated slot 19 extending longitudinally of the plate 12 near the other end thereof. Slot 19 registers with a slot 20 in the board and permits the adjustment of an adjustable stud 21 in all respects similar to the studs 16. A flat neck 22 of this stud below the shoulder 17 is snugly accommodated in the slot, and the shank of the stud 21 may be entered through an enlarged keyhole opening 23 at one end of the slot. In this instance the clamping nut 25 corresponding to the nut 18 is too large to pass through the slot 20 in the board, and bears against the bottom of the board as above described.

The manner of using the device for various purposes will be quite evident. When ironing a cuff for instance, one of the cuff button-holes is hooked over the stationary stud 16 and the adjustable stud 21 is shifted along the slot and locked in position for the reception of the other button-hole with the cuff tautly stretched. The studs hold the cuff while it is being ironed flat, and the cuff is then folded over as indicated in dotted lines in the drawings, so that both sets of button-holes are aligned with and received on the studs. The cuff is again pressed to form the major crease therein. If the cuff has been ironed in the position illustrated, it may be transversely folded to bring all four button-holes over one stud and the ironing operation completed.

It is, of course, to be understood that the device is subject to a wide range of utility; for instance, for holding collars in position, while they are being ironed, and with the adjustable stud, permits ironing of any sized collar, cuff, or any article.

In Fig. 4 I have illustrated a modification of the invention in which the upper end

of the shank 15 instead of being formed with a stud, is formed with a right-angularly disposed clamping plate 30 adapted to overlie and clamp the edge of a garment while the latter is being ironed.

Various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

- 13 1. An ironing board having a slot therein, a stationary stud projecting above the surface of the board, a second stud projecting above the surface of the board and mounted for adjustment along the slot in the board.
- 20 2. An ironing board having a slot therein, a stationary stud projecting above the surface of the board, a movable stud projecting above the surface of the board and mounted for adjustment along the slot, and
- 26 3. means for locking the movable stud in any

desired position of adjustment relative to the stationary stud, said locking means including a threaded shank on the movable stud projecting through the slot and a clamping nut on the end of the shank. 30

3. An ironing board having a longitudinally extending slot therein, a stationary stud projecting above the surface of the board, and a movable stud projecting above the surface of the board and mounted for adjustment along the slot, a plate inlaid in the face of the board and having a slot therein registering with the slot in the board, said movable stud including a reduced neck portion working in the slot in 40 the plate and an enlarged shank portion working in the slot in the board.

4. An ironing board having a slot therein, a pair of relatively adjustable work engaging members, one of said members being 45 fixed to the board, and the other of said members being mounted for sliding adjustment in the slot.

FRANK D. GORMAN.
